OTHER PUBLICATIONS

(**) Term: **14 Years**

Photos of prior art pole sold under the name of Exelens Quick lock.

(21) Appl. No.: **29/223,962**

Primary Examiner—Prabhakar Deshmukh

(22) Filed: **Feb. 23, 2005**

(74) Attorney, Agent, or Firm—Hovey Williams LLP

(51) **LOC (8) Cl. 08-07**

CLAIM

(52) **U.S. Cl. D8/339; D8/382**

The ornamental design for a lock mechanism housing of a telescopic extension pole, as shown and described.

(58) **Field of Classification Search D8/330, D8/331, 341, 342, 343, 339, 382; 70/19, 70/51, 52, 58, 141, 164, 165; 292/256, 262, 292/288, 305, 306; 403/83, 85, 326, 109.1, 403/328, 109.8; 15/144.4, 144.3; D4/139, D4/199**

DESCRIPTION

See application file for complete search history.

FIG. 1 is a perspective view of a lock mechanism housing of a telescopic extension pole embodying our design;

FIG. 2 is a fragmentary, enlarged perspective view of the extension pole depicted in FIG. 1, particularly illustrating the lock mechanism housing of a telescopic extension pole; FIG. 3 is a fragmentary, enlarged perspective view of the extension pole opposite that depicted in FIG. 2;

FIG. 4 is a side elevation view of the lock mechanism housing of a telescopic extension pole depicted in FIG. 1; FIG. 5 is a side elevation view of the lock mechanism housing of a telescopic extension pole depicted in FIG. 1, but at a viewing angle that is perpendicular to that of FIG. 4;

FIG. 6 is a side elevation view of the lock mechanism housing of a telescopic extension pole opposite that depicted in FIG. 4;

FIG. 7 is a side elevation view of the lock mechanism housing of a telescopic extension pole opposite that depicted in FIG. 5;

FIG. 8 is an elevation view of the proximal end of the extension pole depicted in FIG. 1; and,

FIG. 9 is an elevation view of the distal end of the extension pole depicted in FIG. 1.

The broken lines are for illustrative purpose only and form no part of the claimed design.
